1 Claim

ABSTRACT OF THE DISCLOSURE

A quick action battery terminal post clamp for electrical conductor cables characterized by an overcenter cam lever operating on a link embracing the bifurcated ends of a terminal post clamp and an eccentric adjusting cam movable to various predetermined positions operable to enable the clamp to accommodate varying sizes of terminal posts.

BACKGROUND OF THE INVENTION

Field of the invention

The field of the invention is that of a cam actuated electrical connector such as classified in Class 339, Sub-classes 238 and 239.

Description of the prior art

Numerous patents have been granted for quick action cam operated connectors for battery terminals, some of which, lacking adjustment, are unable to cope with varying sizes of automotive battery terminal posts and those which do have adjustment, such adjustment comprises some arrangement of inter-engaging threaded elements which quickly corrode and become useless for that reason. Representative prior art patents include 2,445,940, 2,878,460, 2,887,668, 3,084,306.

SUMMARY OF THE INVENTION

The present invention has for its objective the provision of a lever operated, cam action battery terminal post clamp which is adjustable to accommodate a wide range of terminal post sizes and which is composed of locking and clamping components which are not subject to corrosion by exposure thereof through the acid of the battery. Specifically, the illustrated presently preferred embodiment of the invention involves an eccentrically mounted adjusting component which has a novel interlocking engagement with another component whereby it is prevented from movement from a position to which it has been moved for purposes of adjustment after the clamp has been closed on terminal post.

BRIEF DESCRIPTION OF THE DRAWINGS

The attached drawings, which form a part of the specification, illustrate, by way of example, certain presently preferred embodiments of the invention and in said drawings:

FIGURE 1 is a perspective view of a first presently preferred embodiment of the invention as applied to a battery terminal post,

FIGURE 2 is an enlarged scale top plan view of the embodiment shown in FIGURE 1, the clamping lever means being shown in full lines in the clamping position and in stages of release in broken lines,

FIGURE 2a is a figure similar to FIGURE 2, but showing a detail of fine adjustment to accommodate slight variations in the size of the battery terminal post to be engaged by the connector.

FIGURE 3 is a side elevational view of the connector shown in FIGURE 2,

FIGURE 4 is a transverse section taken on the line 4—4 of FIGURE 2,

2

FIGURE 5 is a partial schematic view demonstrating the range of size accommodation achieved by the device, and

FIGURE 6 is a top plan view of a second presently preferred embodiment of the invention in which the clamping lever movement is across the end of the device rather than along the side of the device where such positioning of the operating lever is necessary or desirable.

DESCRIPTION OF PRESENTLY PREFERRED EMBODIMENT

Referring to FIGURE 1 of the drawings, the first described embodiment of the invention is shown as applied to a terminal post P of a storage battery B and this is probably the principal field of utility of the invention. However, it will be understood that the invention may be employed for other electrical connections where desirable.

The first described embodiment of the invention is disclosed in FIGURES 1 through 5 and comprises a body member 1 formed of a suitably resilient, electrically conductive metal or alloy having a shank portion 2 provided with a longitudinal bore 3 in which the end E of an electrical conductor C is conductively secured by soldering or other appropriate means. The body member 1 is provided with a bore 4 extending therethrough, said bore being tapered to conform to the taper of the battery terminal post with which it is to be used, it being understood that where it is to be used on a cylindrical rather than a taper surface, the bore would be complementary thereto.

The end 5 of the body member 1 at the side of the bore 4 opposite the shank 2 extends to a greater distance from the center line of bore 4 than the portions 6, 6 of the body member bounding said bore intermediate the shank 2 and the end portions 5 and said portion is divided by a slot 7 extending parallel to the bore 4 into clamp engaging arms 8, 8. The side faces 9, 9 of the clamp engaging arms 8, 8 which are opposite the faces thereof which define the slot 7 are of concave configuration as formed about center lines parallel to the center line of the bore 4, said concave faces each terminating in an outer corner 10 and an inner corner 11 spaced from each other a distance which is critical in the use of the device as will presently appear.

The clamping component, generally designated 12, comprises a link 13 of rectangular configuration preferably formed of stainless steel or other corrosion resistant metal and including parallel side members 14, 14 extending between a lever engaging bight 15 and axially aligned end portion 16, 16 which are parallel to the bight 15 and which meet in a bore 17 extending in eccentric relation through a generally cylindrical cam under 18 formed of non-corrosive, non-conductive material said cam having a notched peripheral surface to which further specific reference will be made. The bight 15 is received in a slot 19 in the cam end 20 of a hand lever 21 preferably formed of a rigid but slightly resilient plastic of a character which is acid resistant.

The inner end of slot 19 is of a width in which the link bight 15 is closely but freely received and adjacent to said inner end is slightly narrower so that the link is assembled therein by being snapped into the slot, the resilience of the lever material permitting the said snap-in assembly. The slot 19 extends from the side face of the hand lever which is remote from the body member 1 when the lever extends parallel to the body member as shown in FIGURES 2 and 2a. The cam end 20 of the hand lever is formed with a cam face 22 which is generated about a center line parallel to and slightly offset

toward the handle end of the lever with respect to center line about which the inner end of the slot 19 is generated so that when the lever is moved to the position shown in FIGURES 2 and 2a, there will have been an over center action as will presently appear, the radius of said cam face being not greater than the radius of either of the concave side faces 9, 9 of the body member 1.

The cylindrical cam 18 of a diameter which is at least slightly greater than twice the radial dimension of the concave side faces 9, 9 of the body member and is provided with a series of circumferentially spaced notches 23 adapted to engage one or the other of the corners 10 and 11 defining the end of said concave side faces. The number of said notches is an odd number and the length of the side faces 9 between corners defining the ends thereof is such that when a notch 23 is engaging one or the other of said corners, the other corner will be engaged by the portion of a side of said cam extending between two adjacent ones of said notches. Thus, for example, assuming that the cam 18 is provided with 15 equally spaced notches, the cam may be engaged in 30 different circumferential positions.

Having reference to FIGURE 2, it will be noted that the cam 18 has a notch 23 thereof engaged with an inner corner 11 of the concave side face 9 and that the corner 10 of said side face is disposed between two of the notches 23. In FIGURE 2a, the cam has been rotated only sufficiently (before closing the clamping lever) so that one of the notches 23 engages the corner 10 and the corner 11 is then disposed between two adjacent notches 23. Since the concave faces and their respective corners are mirror image duplicates, the clamping component may be applied with the cam lever thereof at either side as may be most convenient for a particular installation.

In use, a connector of the invention forming the end of a conductor is fitted over the terminal port to which it is to be connected, the handle then being in the open position as indicated at 24 in FIGURE 2. The cam 18 is initially at a point of rotation which presents the least dimension eccentrically to the concave surface with which it is engaged and the cam is then rotated to take up any existing slack. Then upon moving the lever 21 to its closed position, the bifurcated end of member 1 will be caused to grip the terminal tightly. If further tightness is desired, the handle 21 is released and the cam 18 is moved a few notches further in the direction of taking up slack after which the handle is again brought to its clamping or closed position. When the terminal is to be disconnected, the handle 21 is simply moved to its open position and the connector lifted clear of the terminal posts. This simple mode of operation avoids all of the annoyance and loss of time which often occurs in loosening and removing a battery cable connector which is closed by a bolt and nut and on which corrosion has, in effect, welded the nut to the bolt.

In some battery installations in vehicles, the side position of the handle 21 on one or both battery terminals is at least difficult to operate. An alternative clamping opponent 25 may be employed as shown in FIGURE 6 in which similar parts are indicated by the same numbers as is the preceding figures. In this modification, the handle portion is of modified L-shape as viewed in side elevation and in the closed position, extends first generally in the direction of the slot 7 and thence laterally across the end 5 of the body member 1, the slot in which the bight 15 of the link is received and the cam surface being generally comparable with equivalent portions of the first embodiment.

While in the foregoing specification certain presently preferred embodiments of the invention have been disclosed by way of example, it will be understood that changes in modifications may be made therein. For example, the slot 7 which has been shown as being in line with the shank 2 may be located at some other point around the bore 4 or the shank 2 might extend in some direction other than that shown. With these considerations in mind it will be understood that the invention is not to be deemed to be limited to the details of construction thus shown by way of example.

I claim:

1. An electrical terminal connector mountable on a conductor; said connector comprising in combination a body member and a manually operable fastener means 15 detachably mounted on said body member in a selected one of a plurality of positions; said body member being formed of electrically conductive materials having a capacity for being flexed incident to connection to and disconnection from a terminal and including a shank portion having means for attachment of an end of a conductor thereto, and further having a terminal receiving bore extending therethrough, a slot extending through said body member and radially intersecting one side of said bore at 20 a point other than said shank portion, a first, concave, fastener means receiving surface disposed on the exterior of said body member parallel to one side of said slot, a second, concave, fastener means receiving surface, reversely identical to said first concave surface disposed 25 parallel to and at the other side of said slot; said fastener means comprising a rectangular link having side members extending between said concave surfaces at opposite side of said body member, a first end member serving as a pivot means for a manually operable cam lever engageable with one of said concave surfaces and a second end 30 member carrying an eccentrically mounted take up means engageable with the other of said concave surfaces, each of said concave surfaces terminates at each end thereof in a corner and in which said take up means comprises 35 a cylindrical body having a radial dimension not less than the radial dimension of generation of said concave surfaces and having a series of grooves on the outer periphery thereof extending parallel to the axis of said body, and so spaced from one another that when one of said grooves 40 is engaged by one of the corners at the end of the one said concave surfaces in which said take up means is seated, the opposite corner of that concave surface will 45 be disposed between two other of said grooves.
